[57] CLAIM

The ornamental design for a combined guard and injection site for intravenous infusion or the like, as shown.

DESCRIPTION

FIG. 1 is a perspective view of a combined guard and injection site for intravenous infusion or the like showing our new design;

FIG. 2 is a side elevational view thereof, all other sides being identical thereto;

FIG. 3 is a top plan view thereof; and

FIG. 4 is a bottom plan view thereof.

FIG. 2

FIG. 1

FIG. 3

FIG. 4
